UNITED STATES PATENT OFFICE.

ALEXANDER J. LOGUIN, OF NORWOOD, OHIO, ASSIGNOR, BY MESNE ASSIGNMENTS, TO
ALLIS-CHALMERS MANUFACTURING COMPANY, A CORPORATION OF DELAWARE.

CONTACT.

1,238,311.

Specification of Letters Patent. Patented Aug. 28, 1917.

Application filed November 29, 1911. Serial No. 663,103.

To all whom it may concern:

Be it known that I, ALEXANDER J. LOGUIN, a subject of the Czar of Russia, residing at Norwood, in the county of Hamilton and State of Ohio, have invented certain new and useful Improvements in Contacts, of which the following is a full, clear, and exact specification.

This invention relates to contacts.

10 In the use of controllers and various types of switches, it is desirable at times to inspect the contacts. It is sometimes necessary to trim up these contacts and sometimes to replace the contact tips or member 15 forming a part or the whole of contact fingers. It is highly desirable that the contacts be so located and arranged that they may be readily inspected, and removed without the use of tools:

20 It is therefore the object of my invention to provide a simple, inexpensive, and durable contact construction, wherein the contact finger or parts thereof can be removed readily from the main body portion or support 25 of the contact construction without the use of tools and wherein the parts may be readily adjusted.

The various novel features of my invention will be described in the specification 30 and particularly set forth in the appended claims.

The invention is illustrated on the accompanying sheet of drawings, in which Figure 1 is a side elevation of my contact construction; and,

Fig. 2 is a front elevation thereof.

Secured to an insulating base 10, by suitable means, is a terminal plate 11. Secured to this terminal plate by a screw 12 is a 40 conducting supporting member 13 provided with a hook-shaped portion 14 and a bored portion 15 having a shoulder 16 against which the head 17 of a plunger 18 is normally retained. The plunger 18 extends 45 out through one end of the bored portion 15 and is yieldably pressed outwardly of said bored portion by a spring or resilient member 19 which engages the head 17 of the plunger 18 and is retained in an energy- 50 stored position within said bored portion 15 by a pin 20. A contact finger 21, which is preferably rigid, having a contact tip 22, is provided with laterally extending lugs or projections 23 which are adapted to en-

gage and be retained in the hook-shaped 55 portions 14 of the member 13. One end 24 of the substantially L-shaped contact finger 21 is adapted to engage a bolt 25 which acts as a stop for said contact finger. This stop 25 is adjustably secured in the member 60 13 for the purpose of adjusting the contact tip 22 with respect to its co-operating contact surface 26. When the desired adjustment is obtained the bolt 25 is locked in said adjusted position by a nut 27 engaging 65 said bolt 25. Interposed between one end of the contact member 21 and the contact tip 22 is a flexible conductor 28 the other end of which is secured to the member 13 by a screw 29.

70 The contact finger 21, which is pivotally mounted in the hook-shaped portion of the support 13, can be readily removed therefrom by forcing said contact finger against the action of the spring 19 until the lugs 75 or projections 23 of said contact finger are beyond the ends of the hook-shaped portion 14 when the contact finger can be slipped away from its support. It is therefore seen that if it is found necessary to trim 80 the contact tip 22 or to replace the tip or finger, or any parts thereof, the contact finger can be readily removed from its support without the use of tools. The spring 85 19, which may be replaced by a spring of any desired strength, is adapted to take up the irregularities of the contact surfaces of the contacting portions, holding the contact finger in contact with its co-operating contact member, and at the same time serving 90 to retain said contact finger in its support.

There may be various modifications in the precise form and arrangement here shown and described, and I aim to cover all such modifications which do not involve a 95 departure from the spirit and scope of my invention as set forth in the following claims.

What I claim as new is:

1. In combination, a support having a 100 hook-shaped portion and a recess, a spring pressed plunger disposed in said recess, a contact finger having a projection disposed in said hook-shaped portion, and a stop adjustable in said support in a direction 105 transverse to the line of movement of said plunger, said plunger urging the contact portion of said finger into engagement with

a coöperating contact and another portion of said finger into engagement with said stop.

2. In combination, a support having a hook-shaped portion and a recess, a spring-pressed plunger disposed in said recess, a contact finger having a projection disposed in said hook-shaped portion, and an adjustable stop carried by said support, said plunger urging the contact portion of said

finger into engagement with a coöperating contact and another portion of said finger into engagement with said stop.

In testimony whereof I affix my signature, in the presence of two witnesses.

ALEXANDER J. LOGUIN.
